US00D956481S

(12) **United States Design Patent** (10) Patent No.: **US D956,481 S**
(45) Date of Patent: **** Jul. 5, 2022**

(54) **INSULATING DEVICE**

(71) Applicant: **YETI Coolers, LLC**, Austin, TX (US)

(72) Inventors: **Roy Joseph Seiders**, Austin, TX (US);
Derek G. Sullivan, Austin, TX (US);
Erik Steven Larson, Austin, TX (US);
Alex Baires, Austin, TX (US)

(73) Assignee: **YETI Coolers, LLC**, Austin, TX (US)

(**) Term: **15 Years**

(21) Appl. No.: **29/755,364**

(22) Filed: **Oct. 20, 2020**

(57) **CLAIM**

The ornamental design for an insulating device, as shown and described.

DESCRIPTION

FIG. 1 is a top, front, left perspective view of an insulating device showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dot-dash lines represent unclaimed boundaries. The zig-zag broken lines represent zipper teeth and form no part of the claimed design. The even-length broken lines form no part of the claimed design.

1 Claim, 7 Drawing Sheets
